UNITED STATES PATENT OFFICE

164,137

BRASSIÈRE

Lottie L. Schenk, Milwaukee, Wis.

Application May 1, 1950, Serial No. 9,614

Term of patent 7 years

(Cl. D20—4)

To all whom it may concern:

Be it known, that I, Lottie L. Schenk, a citizen of Germany, residing at Milwaukee, in the county of Milwaukee and State of Wisconsin, have invented a new, original, and ornamental design for Brassière, of which the following is a description, reference being had to the accompanying drawing, forming a part thereof.

In the drawing:

Fig. 1 is a front perspective view of a brassière embodying my new design; and

Fig. 2 is a side perspective view of the same brassière.

I claim:

The ornamental design for a brassière, substantially as shown.

LOTTIE L. SCHENK.
